THREAD-CUTTING ATTACHMENT FOR SEWING-MACHINES.

1,010,830.

Specification of Letters Patent.

Patented Dec. 5, 1911.

Application filed July 1, 1907. Serial No. 381,602.

To all whom it may concern:

Be it known that I, JOHN P. WEIS, a citizen of the United States, residing in Nyack, county of Rockland, and State of New York, have invented a new and useful Improvement in Thread-Cutting Attachments for Sewing-Machines, of which the following is a description.

This invention relates to thread-cutting attachments for sewing machines, and has special reference to devices by means of which the threads, or chain of stitches, may be cut or severed at any time it is desired to remove the work from the machine.

Among the objects of my invention may be noted the following: to provide a thread-cutting attachment which is always ready and in position to cut the thread; and which is in such convenient position relative to the stitching-point that the thread can be quickly severed at the end of a stitching operation close to the stitching-point and at any time it is desired to remove the work from the machine; to provide a cutting attachment which, while the machine is in operation, is constantly in motion, whereby it always presents an open jaw and never becomes clogged, and is always active so as to positively cut the thread presented to it; to provide a thread-cutting attachment for sewing machines so located with reference to the stitching-point that it will be in convenient position to slip the thread under its cutting-blade and which, irrespective of whether the machine is running or at a standstill will always be in condition to cut the thread, the ends of which will free themselves from the cutters.

With the above objects in view, and others which will be detailed during the course of this description, my invention consists in the parts, features and combinations of elements hereinafter described and claimed.

In the drawings, which form part of this specification: Figure 1 is a view partially in elevation and partially in section, the section being taken transversely of the machine and beside the feed-bar, illustrating the cutting attachment and its operating mechanism, together with its location in the machine; Fig. 2 is a top-plan view of a portion of the bed-plate of the machine showing the structure of the throat and cloth-plate and part of the thread-cutter actuating

mechanism; Fig. 3 is a perspective view of 55 the thread-cutting plate; Fig. 4 is a detail showing another form of my invention, the view being a partial section and elevation; and Fig. 5 is a section through the cutter.

In the drawings, the numeral 1 indicates 60 the bed-plate forming part of the machine-frame, and 2 indicates the cloth-plate, 3 being a portion of the head of the machine in which the needle-bar 4 and presser-bar 5 operate.

The numeral 6 indicates the needle and 7 the presser-foot shank carrying the presser-foot 8, which is secured to the shank by means of the screw 9.

One of the standards 10, in which the 70 driving-shaft 11 is journaled, is illustrated by dotted lines in Fig. 1 and in top-plan in Fig. 2. A looper-carrier supporting-plate 12 is shown in Fig. 1, in which plate the carrier 13 is journaled in any usual manner, 75 said carrier supporting, at its upper end, the looper 14, which co-operates with the needle 6. The throat-plate 15 is supported by the cloth-plate 2 and is provided with the several slots 16, through which the feed-dogs operate, and also with the tongue 17 over which the stitches may be formed, as in an ordinary overedge-stitching machine. A slide-plate, which covers the usual opening in the cloth-plate, is indicated by 18. 80 On the forward end of the driving-shaft 11, a feed-actuating eccentric is carried, which is surrounded by the strap 19, the other end of which is journaled upon the shaft 20, carried in the upper end of the feed-rocker frame 21, journaled at its lower end in the bed-plate of the machine by means of the shaft 22. The feed-bar 23 is journaled at its rear end upon the shaft 20 at the top of the feed-rocker frame 21 in usual manner, 85 and at its forward end is connected pivotally, as at 24, to the upper end of a strap 25, surrounding an eccentric 26, carried by the driving-shaft of the machine. Thus, the feed-bar is given its feeding or reciprocating movements and its vertical rise and fall, constituting the usual four-motion feed. The forward end of the feed-bar carries the feed-dog 27, which operates through the slots 16 in the throat-plate. 90 Secured to the rear end of the throat-plate 15, at its outer side, and beside the feed-slots, is a plate or ledger-blade 28 held in

place by means of screws 29 with its inner edge projecting slightly over the slot 30 in the cloth-plate, which latter extends parallel with the inner edge of said plate 28.

5 Through the said slot 30 plays the cutter-blade 31, the cutting-edge 32 of which co-operates with the inner edge of the plate 28, so as to produce a shearing cut. The cutter-blade, as shown in Figs. 1 and 3, is in 10 the form of a bell-crank lever and is pivoted at 33 to the throat-plate in the slot 30 thereof, and the depending arm of said lever is bifurcated to provide the opposite parallel prongs 34 between which plays, or with 15 which co-operates, the actuating screw or pin 35, which is tapped into the side of the front end of the feed-bar, as clearly shown in Fig. 1. The cutter-blade is pivoted so as to have its cutting edge overhang the 20 throat-plate and extend toward the rear of the latter, thus co-operating with the plate or ledger-blade 28, so that the two present an open jaw toward the rear of the machine. The cutting-blade projects through the 25 work-plate of the machine, Figs. 1 and 2, at a point out of, and remote from, the path of the feed, said blade extending in the general direction of the feed and parallel therewith, so as to present its back, or 30 non cutting portion, to the work as it is fed and enabling said work to slide over the top of the blade. From the above detail description, the mode of operation of this form of my invention, now to be set 35 forth, will be readily understood.

In the operation of the machine, the feed takes place in the direction of the arrow shown in Fig. 2 and, therefore, the work is advanced across the throat-plate from 40 front to rear. The movement of the feed-bar longitudinally will reciprocate the cutter-blade so as to cause it to co-operate with the inner edge of the plate or ledger-blade 28 and work in the slot 30 of the throat- 45 plate. Thus, while the machine is running, the thread-cutter is kept constantly in operation and will automatically sever the thread, or other material which is run in under the reciprocating blade. The vertical rise and fall of the feed-bar has practically no action on the cutter-blade, for the reason that the slot 36, between the 50 prongs 34, is sufficiently long to prevent the screw 35 from having any action on said blade. At the end of a stitching operation, whether the machine is stopped or not, the fabric will be withdrawn from the rear of the presser-foot and the stitching mechanism will produce a chain of stitches, or else strands of needle-thread, and maybe 55 looper-thread, will be drawn out and will have to be severed, the usual way being to use a pair of scissors. With my cutting-knife in the position indicated and operating as described, the thread can be readily slipped 60

under said reciprocating blade, or under said blade if the machine is at rest, and the thread quickly severed by drawing the same against the cutting-edge 32 of the said knife. Thus, the operator does not have 70 to hunt for his scissors, or depend upon any other implements, such as a jack-knife, to sever the thread or chain of stitches.

In the form of Figs. 4 and 5, the cutter-blade is carried bodily by the feed-bar and 75 the feed is shown as the differential type. The main feed-bar 23, carries at its front end the feed-dog 27, and the supplemental feed-bar 37 with its feed-dog co-operates in usual manner with the bar 23. The feed-dog 27 is extended laterally at 38 so as to provide a support for the thread-cutter 39 secured to the side of said extension 38 by means of screws 40, passing through the cutter-shank 41, the cutter thus moving 80 bodily with said dog. The cutter extends up through the slot 30 in throat-plate 15 and co-operates with the plate 28, the latter operating also in both forms of my invention as a rest for the work and guide for 85 the cutter-blade. Thus, as the four motions are imparted to the feed, the cutter will be operated and the plate 28 will guide said cutter and co-operate with the latter to cut the thread. The cutter in both forms of 90 my invention will always be in contact with the ledger-blade or plate 28 and the two will have a shearing action, the cutting-edge of the active blade running along the cutting-edge of the inactive blade. In both 95 forms the cutting action is positive and certain.

If it is desired to clip the goods for any reason, or catch the same, as is often the case in tailoring, or to trim the same for a 100 short length, these operations can be readily performed by simply running the goods under the reciprocating blade. If the machine is at rest and the feed happens to be at 105 its forward stroke, thread may be slipped against the cutting-edge 32 of the blade or knife and readily cut. This will be clear upon viewing the dotted-line position of the knife or blade indicated by α in Fig. 1.

Having thus described my invention, what 110 I claim and desire to secure by Letters Patent is:

1. In combination with the feeding mechanism of a sewing machine having a feed-dog operating to feed the work in a given direction; a thread-cutting blade mounted so as to have vibratory motion and having its cutting-blade projecting through the work-plate of the machine at a point out of, and remote from, the path of the feed, said blade extending in the general direction of the feed and parallel therewith so as to present its back, or non-cutting portion, to the work as the latter is fed past the stitching position, thus providing a deflect- 115

ing portion to enable the work to slide over the top of the blade; and means for actuating said blade.

2. In combination with the stitch-forming mechanism of a sewing machine, a feeding mechanism having a feed-dog operating to feed the work in a given direction; a thread-cutting device carried by the frame of the machine in rear of the stitching position and having its cutting-blade extending through the work-plate of the machine at a point out of, and remote from, the path of the feed, said blade extending in the general direction of the feed and parallel therewith so as to present its back, or non-cutting portion, to the work as it is fed, thus providing a deflecting portion to enable the work to slide over the top of the blade; and said device having its cutting-jaw normally open in the general direction of the feed of the work; and means for actuating said cutting-blade.

3. In combination with the feeding mechanism of a sewing machine having a feed-dog operating to feed the work in a given direction; a thread-cutting mechanism comprising a cutting-blade extending through the work-plate of the machine at a point out of, and remote from, the path of the feed, said blade extending in the general direction of the feed and parallel therewith so as to present its back, or non-cutting portion, to the work as it is fed, thus providing a deflecting portion to enable the work to slide over the top of the blade; means for actu-

ating said blade; a ledger-blade supported at an angle to the cutting-blade and operating to guide and brace the latter; and said two blades forming a jaw normally open in the general direction of the feed of the work. 40

4. In combination with the feeding mechanism of a sewing machine having a feed-dog operating to feed the work in a given direction; a thread-cutting device comprising two blades supported by the machine-frame and one of which blades is movable relatively to the other and extends through the work-plate of the machine at a point out of, and remote from, the path of the feed, said blade extending in the general 50 direction of the feed and parallel therewith so as to present its back, or non-cutting portion, to the work as it is fed, thus providing a deflecting portion to enable the work to slide over the top of the blade; the two 55 blades providing a cutting-jaw normally open in the general direction of the feed of the work; and the two blades being arranged the one with its edge in contact with the body and cutting edge of the other blade, 60 whereby the movable blade is braced and guided by the other.

In testimony whereof I have hereunto signed my name in the presence of two subscribing witnesses.
